UNITED STATES PATENT OFFICE.

CHARLES L. RAYFIELD, OF CHICAGO, ILLINOIS.

CARBURETER.

1,222,130.

Specification of Letters Patent. Patented Apr. 10, 1917.

Application filed August 23, 1912. Serial No. 716,611.

To all whom it may concern:

Be it known that I, CHARLES L. RAYFIELD, a citizen of the United States, and a resident of the city of Chicago, in the county 5 of Cook and State of Illinois, have invented certain new and useful Improvements in Carbureters; and I do hereby declare that the following is a full, clear, and exact description of the same, reference being had 10 to the accompanying drawings, and to the numbers of reference marked thereon, which form a part of this specification.

This invention relates to carbureters for use in carbureting the air in internal combustion engines. Many devices for the purpose have been heretofore constructed. Some of these have been exceedingly complicated rendering the same so difficult to regulate and adjust as to render their correct adjustment and satisfactory use almost impossible except by trained experts. This difficulty arises in part from the fact that the fuel requirements for the engine, of course, vary with the rate of operation of 15 the engine. For example, where the engine is used for the automobile power plant, the load is extremely variable.

The variations in speed and load occasioned by road requirements necessitates 20 passing instantaneously almost from a high speed, where the engine perhaps is running at the rate of ten to fifteen hundred revolutions per minute, to a low speed, where the operation may be less than fifty per minute, this variation in speed being of course, 25 regulated by the adjustment of the throttle to reduce the fuel supply, and of the spark to vary the timing of the explosion of the respective cylinders. The reverse may, of course, occur immediately after, the throttle 30 being opened and the spark advanced to return to the highest rate of drive of the engine.

Even slight variations in the engine load, 35 of course, vary the fuel requirements for the engine, and, in consequence, many of the carbureters heretofore used are incapable of adjustment to permit the fuel supply to be instantaneously and mechanically adjusted to the requirements of the motor as such requirements vary.

Another serious inconvenience in the ap-

plication of carbureters is found from the fact that the same are usually constructed as a substantially rigid unit, and it sometimes is very difficult to properly connect the same with the man fold pipes leading into the cylinders owing to the exceedingly restricted space in which the installation must occur. In consequence, with certain makes 55 of cars it has been very difficult to install certain makes of carbureters properly to insure their most effective operation.

The object of this invention is to afford a carbureter adapted when once set and adjusted, to enable the supply of fuel to be regulated and controlled instantly to suit the requirements of the engine to which attached so as to permit instantaneous change from the lowest to the highest engine speed 60 or vice versa, without affecting the true, accurate and proper operation of the carbureter, thereby assuring the utmost economy in operation, and the efficient utilization 65 of the fuel supply.

It is also an object of the invention to afford a construction in which the adjustment of the throttle simultaneously adjusts the fuel supply in the carbureter to vary the same to the exact requirements of the engine. 70

An important object of the invention is to afford a plurality of air inlet passages, one of which is mechanically controlled, and another of which is automatically controlled. 75

It is another important object of the invention to afford a constant air inlet sufficient to afford a mixture for the lowest rate of engine draft. 80

One of the very important objects of the invention is to afford a carbureter in which the float feed mechanism and the chamber therefor are adjustable relatively the carbureting apparatus and mixing chamber 85 connected therewith to permit the installation of the device in restricted spaces where otherwise difficult or impossible.

The invention in its preferred form is hereinafter more fully described and illustrated in the accompanying drawings. 90

In the drawings:

Figure 1 is a rear elevation of a device embodying my invention, showing the float

feed chamber in its normal adjustment with reference to the carbureting apparatus.

Fig. 2 is a section on line 2—2 of Fig. 1, and showing the throttle and needle valve 6 open.

Fig. 3 is a top plan view thereof.

Fig. 4 is a section on line 4—4 of Fig. 2.

Fig. 5 is a section taken on line 5—5 of Fig. 2.

Fig. 6 is a section on line 6—6 of Fig. 2, with parts omitted.

Fig. 7 is a detail section of the automatic adjusting cam taken on line 7—7 of Fig. 2.

Fig. 8 is an enlarged, sectional detail 15 illustrating the connection between the float feed chamber and the hydro-carbon supply pipe from the tank.

Figs. 9 and 10 are top plan views of the carbureter embodying my invention, illustrating in full and in dotted lines various 20 adjustments, both right and left, to accommodate the carbureter to the best requirements for installation in restricted spaces.

As shown in the drawings:

25 The carbureting mechanism, comprising a casing containing a mixing chamber, mechanically operated needle valve, and throttle and air inlet valves, is adjustably connected with a float feed chamber to supply 30 the fluid hydro-carbon thereto. The casing 1, for the carbureting mechanism is cast or otherwise constructed to afford a substantially vertical cylindric bore, and said casing is extended downwardly below said bore to 35 afford a tubular cylindric boss 2, having apertures opening through the sides thereof and adapted to afford connection with a float feed chamber as hereinafter described.

Extending upwardly and axially in said 40 bore from within said tubular boss, is a hydro-carbon jet pipe 3, the jet aperture of which is directed upwardly in position to be controlled by a needle valve 4, vertically adjustable in said bore. Said vertical bore in 45 said casing affords the mixing chamber for the carbureter, and opening substantially horizontally outward therefrom is a lower or inlet passage or port 5, the axis of which extends near the orifice in said jet nozzle.

50 As shown, a pipe connection 6, concentric with said air port, is provided on said casing (either integrally therewith or otherwise) to permit of connecting therewith an air supply pipe, which may lead from closely adjacent the cylinders or other location where the temperature of the air is sufficiently high to assist in the carburetion under running conditions. As shown, the bottom of said bore concentric with the spray nozzle, 55 lies slightly below said air port 5, to permit the accumulation of a small quantity of the hydro-carbon in the bottom of the mixing chamber, and, as shown also, a dam or bridge wall 7, is provided in said air port to 60 permit a small quantity of the hydro-carbon

fluid lying in the bottom of said air port or passage, so that the inflowing air will be drawn thereover.

The upper end of said vertical bore affording the mixing chamber, as before described, is somewhat larger than the lower end, and opening outwardly therefrom, and, as shown, substantially parallel with the air port or passage 5, is a cylindric port or passage 8, provided with an external, peripheral flange 70 9, which is extended at each side thereof and provided with a bolt aperture to permit of being rigidly secured in communication with the manifold pipe leading to the cylinders of the engine. 75

Extending rearwardly from said casing and substantially in axial alinement with the throttle port or passage 8, connected with the manifold pipe, is the automatic inlet passage or port 10, as shown of relatively 80 large size, and comprising, as shown, an externally threaded tubular boss communicating as before described, in the upper end of said bore in said casing, and on which is threaded a cylindric sleeve 11, having an integral and centrally apertured head 12, at 85 its outer end. The aperture in said head 12, is relatively large and circular, and the edges of the head at the inner side thereof are beveled inwardly to afford a valve seat. 90 Closing said vertical bore of the mixing chamber at its upper end is a cap or head 13, which is secured in place by means of screws 13*, which extend therethrough and into the body of the casing. Said head is provided with an axial bore therethrough and has connected therewith on the upper and the lower side respectively, an upwardly extending sleeve 14, and an inwardly extending sleeve 15, in which is slidably supported the 100 stem 16, of the needle valve. Said inwardly directed sleeve 15, is provided on its side adjacent the automatic air inlet port, with an internally threaded boss 17, in which is threaded a cylindric stem 18, having a collar 110 19, thereon near its inner threaded end, adapted to jam against the end of said boss, as shown in Fig. 2, to rigidly lock said stem in place.

Said stem 18, lies at the axis of the automatic air inlet port or passage and extends outwardly through the aperture in the head 12. Slidably engaged thereon is a valve closure 20, complementary with the valve seat in said head and adapted to close thereon, 115 and secured on said stem and adapted to bear against said hub 21, on said closure and against said collar after the valve closure has been moved inwardly to afford an initial opening of the valve, is a relatively strong 120 coil spring 22. Also bearing against said collar and against the closure 20, at its inner side at all times, is a relatively weak coil spring 23, adapted to yieldingly resist the initial opening of said closure, and acting 125 130

together with said strong coil spring 22, to resist further opening beyond the limit of such initial opening.

The adjustment of the tension of said springs to vary the resistance thereof, is accomplished by threading the sleeve 11, inwardly or outwardly, thus adjusting the closure 20, on the stem particularly to vary the resistance of the weak spring 23. An integral arm 24, is provided on the cap or head affording the closure for the upper end of the mixing chamber, and a suitable bore is provided in the under side of said arm to receive therein a detent 25, and spring 26, whereby said detent is held downwardly in engagement with the periphery of the sleeve, which is longitudinally fluted, as shown in Fig. 1, to afford engagement for said detent at any of the adjusted positions for said sleeve.

A shaft 27, extends through the throttle passage 8, and air passage 5, before described, and substantially parallel with the axis of the mixing chamber, and secured thereon in the throttle passage, is a butterfly valve closure 28, adapted to control said passage, and secured on said shaft in said air passage, is a butterfly valve 29, which is sufficiently smaller than said passage to permit air inlet around said butterfly valve closure.

When the throttle valve is closed, conveniently (though not necessarily) said closures 28 and 29 are arranged on the shaft in substantially the same plane, and the air valve closure 29, is sufficiently smaller than the air passage to permit a clearance between the edges thereof and the walls of the passage, of a small fraction of an inch to insure an air supply at all times for the lowest possible degree of opening of the throttle. As shown also, such clearance is indicated by slightly cutting away the lower edge of said closure to afford a slightly greater clearance at the bottom, so that inflowing air drawn over the bridge wall 7, and beneath said edge is drawn through any of the hydro-carbon liquid that may be in the bottom of said air passage, thereby agitating such liquid and assisting in the carburetion of the air.

Secured on the upper end of said shaft 27, is a throttle lever 30, for operating said valves, and means are also secured on said shaft and operated by said lever therewith to adjust the needle valve proportionately to the degree of opening of the throttle to supply the requisite amount of the hydro-carbon for the running conditions of the engine and its throttle adjustment. For this purpose, as shown, a block 31, is secured on said shaft and is provided with a transverse bore therethrough, as shown in Figs. 6 and 7, and threaded through said bore and lying in a recess or notch in said shaft 27, is a screw shaft 32, the ends of which are ro-

tatably engaged in the parallel arms 33 and 34, of a cam 35, the outer or cam faces of which lie at substantially a right angle with each other and are connected by a curved or rounded surface at the apex.

Said block 31, is abutted to receive the inner edge of said cam member to permit the same to slide on said block, as shown in Fig. 6, and said screw shaft 32, is provided at its outer end with a milled head 36, for manual engagement to permit the adjustment of said cam transversely the shaft 27, and to vary the throw of the cam. As shown, said screw shaft adjacent the head is longitudinally fluted at 34^a, and a spring 80 pressed detent 37, is engaged in the arm 34, of the cam, and, engaging said roughened or fluted portion of the screw shaft, acts to hold the cam normally in adjustment or prevents the varying of the adjustment through 85 any vibration to which the parts may be subjected, thereby locking the cam in its adjustment.

The stem of the needle valve is provided near its lower end with a collar 38, and a spring 39, shown as a coiled spring, bears at its lower end against said collar and at the lower end of the sleeve 15, and acts to hold said needle valve closure normally seated. Connections are afforded between said cam 35, and said needle valve stem to open the needle valve proportionately with the adjustment of the throttle and also to open or raise the same, as desired, for the initial starting of the engine.

For this purpose, as shown, the upper end of said stem is longitudinally bored and for at least a part of its length, screw threaded at its upper end, as shown in Fig. 2, and a longitudinal slot provided through said stem into said bore. Threaded in the bore of said stem is a set screw 40, having a milled head 41^a, at the upper end thereof for manual engagement, and secured at the inner end of said set screw and at the axis of the bore in said stem, is an anti-friction ball 41, which at all times rests upon one of the arms 42, of a bent or U shaped lever, the other arm 43, of which is engaged by the arm 44, of a bent lever, which is fulcrumed 415 on the head 13, and the other arm 45, of which extends forwardly and bears against the outer face of said cam, so that the set screw 40, having been properly adjusted, rotation of the throttle shaft 27, by its lever, 120 actuates the needle valve closure to lift the same with the opening of the throttle and to close the same with the closing of the throttle.

Secured on the upper end of the needle valve stem, is a bracket 46, extending rearwardly therefrom, and at its upper and rear end provided with a slide aperture therethrough, through which extends a wire 47, the other end of which is connected with a 130

5 crank 48, secured on the head 41^a, of the set screw 40. In starting the engine from a state of rest, it is desirable to flood the carbureter, and for this purpose the operator, by means of said wire, may rotate the set screw 40, sufficiently to thread the same inwardly for a part of one revolution, thereby lifting the needle valve closure on the arm 42, of said lever and permitting the 10 hydro-carbon fluid to flow into the mixing chamber. Of course, when the engine is started, the screw shaft is returned to normal adjustment by means of said wire 47.

15 The float feed chamber comprises a casing constructed of cast metal or in any suitable manner and material, having a removable cap or head 49. The casing of the float feed chamber is extended at its bottom to afford upper and lower parallel walls 50 and 51, 20 which are apertured to fit on the cylindric boss 2, at the lower end of the mixing chamber, as shown in Fig. 2. Metallic or other suitable packing washers 52 and 53, are engaged on said boss to pack the joints afforded at the connection of said boss therethrough, and a screw plug 54, is inserted to close the lower end of said tubular boss affording a part of the communication between the float feed chamber and the mixing 30 chamber.

35 A cylindric stem 55, is extended through the cap 49, of the float feed chamber, and threaded into the bottom thereof and slideable on said stem in said chamber, is the feed float 56, which may be constructed of any buoyant substance or may be a thin hollow sheet metal float, as preferred. As shown, a vertical passage or bore is provided in the casing at one side of the float 40 feed chamber in alinement with the pipe connection 57^a, whereby the line pipe 57, from the tank is connected therein. Said pipe connection 57^a, discharges into said vertical passage through a restricted opening 45 or passage and the metal surrounding the same is shaped to afford a valve seat.

50 Threaded in the upper end of said passage, is a closure or head 58, having a central bore therethrough, and slidably extending therethrough is a stem 59, the lower end 60, of which is tapered to close the aperture in said pipe fitting 56, affording a needle valve. A nut 61, is threaded on said stem and a weak spring 62, bears at its upper end 55 against the head or closure 58, and at its lower end bears against said nut and acts to hold the needle valve normally seated.

60 Fulcrumed upon a pintle 63, extending transversely between the axis of the float feed chamber and said needle valve stem, is a lever 64, yoked at each end, one of the yoked ends thereof receiving the stem 55, therein, upon which the float 56, slides, and provided with upwardly directed transverse 65 ribs 65, to support the float with minimum

friction, the other or outwardly directed yoked end being also provided with V shaped, upwardly directed ribs 66, and engages beneath a nut 67, threaded on said stem, and which may be held in rigid and 70 permanent adjustment by a jam nut 68, threaded thereagainst.

75 A suitable air inlet port or passage 69, is provided through said head 58, to permit the inflow of air with the outflow of the hydro-carbon fluid to the mixing chamber. Mounted adjustably upon said head 58, is a bracket 70, upon which is fulcrumed a lever 71, which engages beneath the head of the stem 59, as shown in Fig. 2, and is provided with one arm 72, adapted for manual engagement to permit said needle valve to be raised in flooding the carbureter, and provided with an arm 73, normally pressed by a spring 74, carried on said bracket, and 80 which holds said lever normally out of action.

85 As shown, a tubular boss 75, is provided integral with the floor or bottom of the float feed chamber, and apertured therethrough to communicate therein and closed by a screw plug 76. The removal of said screw plug permits the float feed chamber to be drained at any time for the removal of water or dirt.

90 The operation is as follows: In installing the carbureter, the float feed chamber may be arranged as shown in Figs. 1, 2 and 3; that is to say, substantially in alinement with the throttle passage and air inlet ports, 100 or, if desired, or the requirements of the available space render it necessary, the screw plug 54, may be loosened slightly and the float feed chamber swung either to the right or left with reference to the mixing 105 chamber, as shown in Figs. 9 and 10, it being possible, as shown in dotted lines in Figs. 9 and 10, to adjust the float feed chamber through an angle of 180 degrees, shown in Figs. 1 to 3 inclusive, and of course, to 110 any position intermediate said extreme positions.

115 The screw plug 54, is again set up after the adjustment is effected, rigidly engaging the float feed chamber with the carbureting chamber. The bracket 70, is also rotatably adjusted upon the plug 58, for the float feed needle valve, so that whatever the adjustment of the float feed mechanism relatively to the carbureting mechanism, the 120 lever arm 72, may be properly directed to be operated from the dash by means of a suitable connection not shown, for example, a wire similar to the wire 47, before described, which may be hooked in the aperture in said arm.

125 In adjusting the carbureter, the adjustment of the needle valve is effected by means of the set screw 40, to meet the requirements of the engine at its lowest throttle position— 130

that is to say, when the engine shaft is barely turning over, at which time the lever end 45, will bear upon the longer straight side of the cam somewhat as indicated in Fig. 6.

5 Care is taken to adjust said needle valve in this manner, so that the engine receives the necessary fuel supply to operate perfectly at such low rate of speed. The throttle is now fully opened, and the spark advanced for maximum speed. This brings the lever end 45, into bearing on the other straight side of said cam, and the cam is adjusted by means of its screw shaft 32, 10 varying the throw of the lever, and, of course, varying the opening of the needle valve by means of said cam lever until the engine operates perfectly and without back firing or missing at such high rate. At the 15 same time, of course, the automatically controlled air valve may be adjusted to supply the requisite air supply over the requirements at the low running position.

Having secured a satisfactory adjustment 20 for maximum speed, the shape of the cam is such that the throttle may be shifted from full open position to any intermediate position, with the effect of proportionately reducing or increasing the supply of the 25 hydro-carbon liquid. Inasmuch also, as the air valve 29, is secured on the same shaft with the throttle valve, the air supply is likewise varied simultaneously to the best running conditions for the engine at whatever speed it be operated.

Of course, before the adjustment of the valves, as before described, the float is set 30 to permit the float feed needle valve to close under the action of its spring, and the buoyancy of the liquid in said chamber, when 35 the level of the liquid in said chamber is just below the orifice of the nozzle 3. This adjustment, however, is very easily effected by means of the nuts 67 and 68, and having once been adjusted, for example, at the factory, need not be further disturbed.

Should it be required to flood the carbureter, the lever arm 72, is actuated in any suitable manner to raise the stem 59, opening 40 said needle valve, and holding the same open independently of the position of the float until the desired amount of gasoline or other hydrocarbon fluid has flowed into said chamber. Of course, an adjustment of the set 45 screw 40, by means of the rod 47, is effected at the same time, permitting the excess gasoline to flow into the mixing chamber. When 50 said rods are released, the parts return immediately to normal adjustment and the operation is as before described.

I claim as my invention:

1. A carbureter of the class described embracing an upright mixing chamber and automatically and mechanically controlled laterally directed air inlet ports communicating 65 therein, a float feed chamber adjustably and eccentrically connected therewith, and communicating therein, and a needle valve controlling the communication between the same.

2. A carbureter embracing a mixing chamber, a mechanically adjustable needle valve therein, an upper throttle valve, a lower air inlet valve, a shaft to which both are secured to operate the same simultaneously, connections between the throttle valve and the needle valve acting to open said needle valve proportionately with the degree of opening of the throttle valve and air valve, an automatic air inlet valve mounted in an inlet to 80 said mixing chamber aligned with the passage controlled by said throttle valve, and a float feed chamber eccentrically, adjustably and sealingly connected to said mixing chamber to admit fuel to said needle valve.

3. A carbureter embracing an upright mixing chamber, a float feed source of hydro-carbon supply opening through the bottom thereof and adjustably and eccentrically connected therewith, a needle valve controlling the same, a throttle shaft journaled parallel the axis of the mixing chamber, a throttle valve secured thereon near the top of the mixing chamber, an air valve below the 90 throttle valve and above the bottom of the 95 mixing chamber, a lever for operating said valves simultaneously, operative connections for opening said needle valve proportionately with the opening of the throttle and air inlet valves, and an automatic air inlet 100 valve arranged substantially in alignment with the throttle valve.

4. A device of the class described embracing a vertical mixing chamber, a float feed chamber eccentrically and adjustably 105 connected therein, a needle valve positioned to control said source of supply, a throttle valve and an air valve rigidly connected together, connections between the throttle valve and needle valve, and a single lever 110 connected to simultaneously open the throttle, the air valve, and the needle valve proportionately.

In testimony whereof I have hereunto subscribed my name in the presence of two 115 subscribing witnesses.

CHARLES L. RAYFIELD.
